UNITED STATES PATENT OFFICE.

JAMES E. THOMSON, OF BUFFALO, NEW YORK.

SEALING PRESS, PUNCH, &c.

SPECIFICATION forming part of Letters Patent No. 228,572, dated June 8, 1880.

Application filed April 16, 1880. (No model.)

To all whom it may concern:

Be it known that I, JAMES E. THOMSON, of Buffalo, State of New York, have invented a new and useful Improvement in Sealing Presses, Punches, Griping-Tools, Shears, &c.; and I hereby declare the following to be a full, clear, and exact description thereof, reference being had to the accompanying drawings, making part of this specification, and in

10 which—

Figure 1 is a perspective view of a sealing-press with my improvements attached. Fig. 2 is a sectional view of the same; Fig. 3, detail to be referred to.

15 My invention relates to the means of applying and gradually increasing the power of a sealing-punch; and it consists in the combination of devices hereinafter explained and claimed.

20 To enable others skilled in the art to make and use my invention, I will proceed to describe the exact manner in which I have carried it out.

In the drawings, A represents the sealing-levers, pivoted together in the usual manner, 25 and B represents the hand-levers, pivoted to the levers A at a, and pivoted together at b. These hand-levers are each formed with an inwardly-arranged cam, e, as shown in Fig. 2, and these cams are brought into play on each 30 other as the hand-levers approach, whereby a gradually-increasing power of great force is transmitted directly from the hand-levers to the sealing-point.

35 I am aware that a somewhat similar increase of power on the punching-lever has been obtained by interposed independent toothed eccentrics connected by links and

separated pivots; but such is not my invention.

40 In the outer ends of the punching-levers are placed the dies C, provided with the annular groove c, into which fits the spring-pin D, whereby I am enabled to quickly change the die when desired by simply touching the 45 pin, thereby avoiding the use of screws or screw-drivers.

To the inner side of the hand-levers I secure the flat springs E, the inner end of the one being bifurcated at d, and the other being 50 supplied with a tongue, d', fitting into the bifurcation, as shown in Fig. 1. These two springs, bearing against each other and having an easy play between the levers, secure a free motion to the levers at all points of their 55 movement.

Having thus described my invention, what I claim as new, and desire to secure by Letters Patent, is—

1. The sealing-levers A, in combination with 60 the hand-levers B, having the integral cams e, substantially as and for the purpose set forth.

2. The sealing-levers A, provided with the spring-pins D and grooved dies C, in combination with the hand-levers B, having the integral eccentric cams e, substantially as and for the purpose set forth.

3. The levers A and B, in combination with the springs E, provided with the bifurcation 70 d and tongue d', substantially as and for the purpose described.

JAMES E. THOMSON.
